UNITED STATES PATENT OFFICE.

JOSEPH STARR, OF NEW LONDON, CONNECTICUT.

COIN-OPERATED VENDING-MACHINE.

957,720.

Specification of Letters Patent. Patented May 10, 1910.

Application filed March 24, 1909, Serial No. 485,382. Renewed March 30, 1910. Serial No. 552,414.

To all whom it may concern:

Be it known that I, JOSEPH STARR, a citizen of the United States, residing at New London, in the county of New London and 5 State of Connecticut, have invented certain new and useful Improvements in Coin-Operated Vending Machines, of which the following is a specification.

This invention relates in general to coin-operated vending machines and particularly to machines for vending tubular drinking cups and the like articles; my immediate purpose being to simplify, cheapen and improve the means for delivering the said 15 tubes, one at a time and also to improve the mechanism immediately related to the releasing and locking devices.

In order to describe my said invention clearly I have provided the annexed drawings, in which—

Figure 1 is a perspective view of a machine embodying my said improvement and Fig. 2 is a similar view with the housings largely broken away, or removed, to disclose 20 the operative parts of the machine. Fig. 3 is a front side elevation of the lower half portion of the machine and Fig. 4 is a vertical, sectional, view taken between the confronting ends of the two stacks of tubes, 25 that is to say, on the line 4—4 of Fig. 3. Figs. 5, 6 and 7 are outer face views of the coin chute and of the devices which, co-acting with a suitable coin, permit the wheel 14 to revolve a predetermined distance and deliver a roll for each coin deposited in the 30 machine. Fig. 8 is a sectional view taken on the line 8 of Fig. 5 and Fig. 9 is a sectional view taken on the line 9 of Fig. 7. Fig. 10 is a plan view of the machine with the top 35 removed to illustrate the arrangement of the tube chutes.

By reference to said Fig. 10 and to Fig. 4, it will be understood that two parallel series of chutes are provided; each series 40 being composed of three chutes that discharge their contents, by gravity, upon a notched or fluted delivery wheel which is adapted to be moved a partial revolution upon the insertion of each coin, as I shall 45 explain more fully hereinafter; the tube-receiving flutes of one delivery wheel being offset from those of the other wheel so that a tube is discharged first from one series of chutes and then from the other series. By 50 thus providing a plurality of chutes in each series I am able to produce a machine in

which a large number of tubes may be stored in reasonably small space.

In the annexed drawings the reference numeral 10 indicates a substantial base upon 60 which is mounted a box-like structure 11 of considerable height within which are located the vertical chutes which I have already referred to as arranged in two parallel series; each series including a plurality of chutes, 65 here shown as three in number. Each of said chutes is composed of fixed, vertical, parallel guide rails 12 so spaced apart that the tubes 13 may travel downward therebetween by gravity as the lowest tubes are 70 successively removed. The delivery wheels are denoted by the numerals 14 and are each formed with flutes or notches 15 of proper size and shape to receive freely a single tube; one wall of each notch being formed 75 as a hook or beak 16 which operates as a pocket into which the tube drops when the notch or pocket moves into register with the vertical chutes in which the supply of tubes is stored. When the wheel 14 moves forward the said beak 16 also enters readily between the selected tube and the tubes above it in the chute, operating substantially as a wedge. This beak, as it cuts off the lowest tube, immediately assumes the load of the 80 superimposed rolls in the chute and thus relieves the selected tube from such load. Without such beak the points on the notched wheel are liable to engage the side of the selected roll and crush the same instead of 85 readily separating it from the tubes above it.

Attention is now directed particularly to Fig. 4 in which it will be seen that the wheel 14 is carrying three tubes all of which have been removed from the right hand chute for, 90 it should be understood, that the tubes in the middle and left hand chutes will not be disturbed until the right hand chute is emptied for the obvious reason that the pockets or notches in the delivery wheel are filled before they move into coincidence with the middle and left hand chutes. Thus it will be seen that the right hand chute will be emptied first, then the middle chute and, finally, the left hand chute. A guard plate 100 or shield 17 prevents the tube from leaving the pocket in wheel 14 until the proper time when said tube falls, by gravity, upon an incline 18 and rolls out of the housing through an opening 19. The notched wheels 14 of 110 both series are fixedly secured to a shaft 20 and also secured to said shaft, outside the

main housing, is a disk 21 which is formed with peripheral notches 22 and with intervening notches or holes 23 which latter are adapted to receive the end of a spring-
5 pressed bolt 24 which operates to lock the disk 21 and the wheels 14 against rotation until such time as it is desired to deliver a tube 13. Hinged at 25 is a lever 25^a whose mid-portion is pivoted to the bolt 24 and
10 whose free end projects into the path followed by the coin (see Fig. 5).

The coin-receiving chute is indicated by the numeral 26 and its lower end is so located with respect to the described disk 21
15 that the coin enters one of the notches 22 as it slides down the chute and rests also against the free end of the described lever 25^a, being thus prevented from passing into a curved path provided between the disk 21
20 and a concentric plate 27.

Loosely mounted upon the outer end portion of shaft 20 is a hub 28 having a weighted pendulous extension 29 and an operating handle 30, and having also a radial arm 31
25 whose free end terminates in a lateral stud 32 that extends into the circular path traversed by the coin.

In the Fig. 5 the stud 32 lies behind (that is to say above) the coin and in such relation to said coin that, when the handle 30 is rocked toward the left hand, the coin will be forced downward sufficiently to crowd the lever 25^a back and thus withdraw bolt 24 from engagement with disk 21 (see Fig. 6).
30 During the passage of the coin downwardly, along the curved path, the coin lies partially in the notch 22, causing the disk 21 to move with the coin and thus rotating the wheels 14 sufficiently to deliver a tube. The coin
35 is then left in the position seen in Fig. 7 and serves as a lock to prevent the accidental disarrangement of the operative parts, while the arm 31 (by reason of the counter-weight 29), swings back to its normal position (as in Fig. 5). When the next coin is dropped into the machine, and is forced downward, in the manner just described, the first coin is carried forward until it passes beyond the curved plate 27 when it drops by gravity
40 into a receptacle 33. Thus it will be seen
45

that the coin serves to lock the operative parts to prevent the surreptitious rotation of the delivery wheels 14 and it also serves to unlock the delivery mechanism.

The operation of my described machine is 55 as follows: assuming that the two series of tube-receiving chutes have been filled with tubes. When a coin is dropped into the chute 26 it passes downward, by gravity, until it enters one of the notches 22 and 60 also engages the free end of the lever 25^a. The handle 30 is then grasped and rocked toward the left hand, as here shown, sufficiently to bring the stud 32 on arm 31 into engagement with the edge of the coin. Continued movement of the arm and stud forces the coin downward along the curved path between disk 21 and plate 27, thus releasing the bolt 24 and causing the disk 21, shaft 20 and connected wheels 14 to be rotated sufficiently to deliver a tube from (for example) the right hand series of chutes. The next partial revolution of the wheels 14 will operate to deliver a tube from the left hand series of chutes and this operation may be 70 75 repeated until all of the tubes in both series of chutes have been discharged, one at a time, from the machine.

Having thus described my invention I claim:—

In a vending machine, the combination with a multi-chambered vertically-disposed tube-supporting chute, of a notched delivery wheel disposed beneath said chute, said wheel having at one side of each of its 80 notches a hook or beak having a wedge-shaped point forming a pocket to receive a tube and adapted to enter between the selected tube and the tubes above it in the chute and to act as a cut-off and a support 85 for the superimposed rolls in the chute, whereby the selected tube is relieved from such load, and a guard plate following the contour of said wheel to prevent a tube from leaving its pocket and intermittently-actuated locking mechanism.

JOSEPH STARR.
